FIRE EXTINGUISHING SYSTEM

Daniel A. Gillen, New York, N. Y.

Application November 19, 1935, Serial No. 50,603

5 Claims. (Cl. 169—29)

This invention relates to a fire extinguishing system, and has for an object to provide a system or structure which may be applied or associated with a single room or with many rooms and caused to act automatically or by a hand control.

Another object of the invention is to provide a fire extinguishing system adapted for a single room wherein the parts are mounted so as to distribute an extinguishing fluid which will produce a smothering gas when the device is functioning.

An additional object, more specifically, is to provide a container at the top of the room with electric control means for causing the same to function.

15 In the accompanying drawings:

Fig. 1 is a vertical sectional view through a tank and associated parts forming the principal part of the invention, the same being shown applied to a ceiling of a room;

20 Fig. 2 is a bottom plan view of the structure shown in Fig. 1;

Fig. 3 is a bottom plan view of the tank shown in Fig. 1; and

25 Fig. 4 is a diagram showing the electrical connections and certain associated devices.

Referring to the accompanying drawings by numerals, 1 indicates a spider which is provided with an outer ring structure 2, a central section 3, and a number of spokes 4. Suitable screws 5 secure the spider 1 permanently to the ceiling 6 and on this spider all of the other parts are mounted. In Fig. 1 it will be observed that the tank 7 is provided with a flange 8 through which the various machine screws 9 extend for clamping the container rigidly to the spider 1. The container at the upper central part is provided with a chamber 10 in which the electric motor 11 is positioned, said motor having a flange 12 through which the screws 13 extend, said screws 20 being threaded into the spider 1. The tank 1 is also provided with a central tube 14 through which the armature shaft 15 extends whereby this shaft may be clamped by any suitable means, as for instance the set screw 16, to the hub 17 45 of a distributing member 18.

It will also be noted that the side wall of the container is provided with an annular groove 19 in which a rubber or other packing 20 is fitted, whereby liquid can not pass upwardly within the side wall 21 of member 18. The side wall 21 is provided with an annular flange 22 overlapping the flange 23 of a ring bracket 24, whereby the various anti-friction balls 25 may be positioned between the two flanges and thereby ro-

tatably support member 18. Member 18 at the lower part is provided with a number of apertures 26 and at the periphery with a number of apertures 27. It will be noted that the lower part or bottom of member 18 is spaced from the bottom 28 of tank 1 whereby there will be presented a chamber 29 into which the liquid 30 moves when it leaves the tank. From chamber 29 liquid will flow through the aperture 27 because the member 18 will be rotating at a comparatively high speed. The bottom 28 of tank 1 is provided with a pair of annular weakened tracks 31 and 32 which merge into sockets 33 and 34. These sockets extend upwardly as shown in Fig. 1 and accommodate the sharp pointed ends of the cutters 35 and 36 which are clamped to member 18 by suitable bolts or rivets 37 and 38.

When the parts are in the position shown in Fig. 1 and motor 11 begins to function it will rotate member 18 and the first revolution will 20 result in the cutters or knives 35 and 36 cutting through the tracks 31 and 32. This will allow the liquid 30 to freely pass downwardly to chamber 29 and be sprayed or distributed as the distributing or spray member 18 continues to rotate. 25 The liquid 30 is intended to be some form of fire extinguishing solution or liquid which will produce a smothering cloud adapted to deprive the fire of oxygen whereby it will be extinguished. As the device is carried by the ceiling of the room 30 the spraying of the liquid at that point will result in a desired conversion of the liquid into a smothering gas. As this gas is heavier than air it will gradually move downwardly and extinguish any fire that might be in the room. After 35 the device has once functioned it will be necessary to remove member 18 and place a new tank in position with a new supply of liquid. After this has been done member 18 is replaced and the device is ready for a second use.

40 The device may be caused to function by various means, but preferably by one or more thermostatic switches and also by a manually actuated switch. As shown in Fig. 4 the motor 11 is connected by wires 39 and 40 with source of current 41 through either of the switches 42 or 43. Also a sounding device, as for instance bell 44, is connected with source of current 41 and the circuit thereof is closed by either of the switches 42 or 43. It will be understood that either of the switches 45 may be placed at any desired point in a room and, if desired, a number of the automatic heat control switches may be connected up to the same circuit so that if a fire starts in any part of the room 50 near a switch the response will be almost im- 55

mediate. When either switch is closed the motor 11 will begin to rotate and upon the first rotation the tracks 31 and 32 will be cut so that the fluid will immediately begin to flow into chamber 29. As member 18 continues to rotate the liquid will be sprayed so as to be evaporated or formed into a cloud whereby the fire is extinguished.

I claim:

1. A fire extinguishing system including a fixed liquid carrying tank, a rotary liquid distributing member for distributing liquid from said tank, a cutter carried by said distributing member and positioned to cut an opening in said tank when the distributing member is rotated, an electric motor for rotating said distributing member, and a plurality of means for closing the circuit of said motor, one of the last mentioned means being a manually actuated switch and the other a heat actuated switch.
2. A fire extinguishing system including a liquid container, a rotating distributing member partly surrounding the container and provided with distributing apertures, a cutting structure carried by said distributing member and positioned to cut an opening in said container when the distributing member is rotated, and an electric motor connected with the distributing member for rotating the same.
3. A fire extinguishing system including a spider adapted to be secured to the ceiling of a room, a container adapted to be permanently connected with said spider, an electric motor connected permanently to the center of said spider, said container being adapted to be provided with a fire extinguishing liquid, said container also being provided with a passageway extending centrally therethrough, said motor having a shaft

extending through said passageway, said container having a pair of parallel tracks of comparatively thin material in the bottom, a pair of knives adapted to cut said tracks so that part of the bottom will move away from the remaining part for permitting said liquid to flow from the container, a distributing member having an annular side wall and a foraminous bottom, means for rigidly securing said bottom to said shaft so that the distributing member will rotate with said shaft, and means for clamping said knives to said distributing member.

4. In a fire extinguishing system, a fixed container, a rotating distributing member having an annular wall surrounding said container, means coacting with said wall for rotatably supporting the distributing member, said annular wall merging into a substantially flat bottom having perforations, said wall being also provided with perforations near said bottom, a cutting structure carried by said bottom adapted to cut part of the bottom of said container when the distributing member is rotated, and means for rotating said distributing member.

5. A device for spraying fire extinguishing liquid from the ceiling of a room comprising a liquid container, means for cutting the bottom of the container to allow the liquid to flow therefrom, a foraminous rotating member for distributing the liquid from the container over a wide area, said cutting means being carried by said rotating member and positioned to cut part of said bottom when said foraminous rotating member is rotated, and means for rotating said rotating member.

DANIEL A. GILLEN.
